DESIGN FOR A SHOE

Saveria Macri, Brooklyn, N. Y.

Application August 3, 1940, Serial No. 94,194

Term of patent 3½ years

To all whom it may concern:

Be it known that I, Saveria Macri, a citizen of the United States and resident of Brooklyn, in the county of Kings, in the State of New York, have invented a new, original, and ornamental Design for a Shoe, of which the following is a specification, reference being had to the accompanying drawing, forming a part thereof.

The essential features of the design reside in the parts shown in full lines.

I claim:

The ornamental design for a shoe, as shown and described.

SAVERIA MACRI.
